CLAIM

The ornamental design for a side-guard for inside of a flexible bag, as shown and described.

DESCRIPTION

FIG. 1 shows a top perspective view of a side-guard for inside of a flexible bag;

FIG. 2 shows a front elevation view thereof;

FIG. 3 shows a top plan view thereof;

FIG. 4 shows a bottom plan view thereof; and,

FIG. 5 shows an exploded view thereof.

The broken lines shown in the drawings are for environmental purposes only and form no part of the claimed design.
